In a fuel injection valve, a cylindrical valve body has a valve seat protruding radially inward out of an inner wall thereof and a needle supporting cylindrical inner wall. A nozzle needle is fixed to the armature so as to move together with the armature, while being supported slidably by the needle supporting cylindrical inner wall. The nozzle needle is provided with a valve portion to be seated on the valve seat when a coil is de-energized and inside thereof with a cavity into which fuel is introduced. A fuel accumulation bore is provided between inner circumference of the cylindrical valve body and outer circumference of the nozzle needle. With the construction mentioned above, the nozzle needle is provided with an opening through which the cavity communicates with the fuel accumulation bore.

FIG. 6

PRIOR ART

FUEL INJECTION VALVE

CROSS REFERENCE TO RELATED APPLICATION

This application is based upon and claims the benefit of priority of Japanese Patent Application No. 2000-139702 filed on May 12, 2000, the content of which is incorporated herein by reference.

BACKGROUND OF THE INVENTION

1. Field of the Invention

The present invention relates to a fuel injection valve for an internal combustion engine (hereinafter called as an engine).

2. Description of Related Art

As shown in FIG. 6, a conventional fuel injection valve 100 has a nozzle needle 101 that is slidably and reciprocatingly supported by a sliding portion 102. The sliding portion 102 is provided with a plurality of cuts for forming fuel passages. The cuts of the sliding portion 102 also serve as vapor passages through which vapor generated by heat near injection holes moves toward a side of fuel upstream. A contact portion 103 formed at an end of the nozzle needle 101 on a side of fuel injection may be seated on a valve seat 105a formed in a valve body 105.

An armature 111 is connected with the nozzle needle 101 at a position facing a stator 110 and is biased in a valve closing direction by a spring 112. Since the armature 111 and the sliding portion 102 are slidably and reciprocatingly supported by the valve body 105, the nozzle needle 101 can make a reciprocating movement accurately along a center axis thereof. Generally, the stator 110 and the armature 111 are made of lower toughness material and are plated with, for example, chromium to form thin film thereon. When a coil 115 is energized, the armature 111 is attracted toward the stator 110 against biasing force of the spring 112. Accordingly, the nozzle needle 101 leaves the valve seat 105a so that fuel is injected from the injection holes. When the coil 115 is de-energized, the contacting portion 103 is seated on the valve seat 105a to finish fuel injection.

It is important for better fuel consumption that fuel is supplied to the engine at an adequate timing during a period when an intake port of the engine is opened. Therefore, the fuel injection valve is required to have quick response characteristic that is largely affected by mass of a moving member including the nozzle needle 101.

According to the conventional fuel injection valve 100, the nozzle needle 101 is integrally provided with the sliding portion 102 having the cuts, whose maximum outer diameter is larger than that of the contact portion 103, for securing the fuel and vapor passages. Accordingly, among the nozzle needle 101, the sliding portion 102 and the armature 111, which constitute the moving member, the sliding portion 102 adversely affects on the quick response characteristic of the fuel injection valve because of larger mass thereof.

Further, formation of the chromium thin film on portions where the stator 110 and the armature 111 come in contact with each other results in higher manufacturing cost of the fuel injection valve.

SUMMARY OF THE INVENTION

An object of the invention is to provide a fuel injection valve in which weight of a nozzle needle is relatively light

and mass of a movable member constituted by the nozzle needle and an armature is smaller so that quicker response characteristic of the injection valve is secured.

To achieve the above object, in the injection valve having a housing, a stator, an armature and a coil for exerting electromagnetic attracting force on the armature, a cylindrical valve body, which is provided with at least an injection hole, has a valve seat protruding radially inward out of an inner wall thereof, which is positioned on a side of the stator with respect to the injection hole, and a needle supporting cylindrical inner wall, which is positioned on a side of the stator with respect to the valve seat. A nozzle needle is fixed to the armature so as to move together with the armature in the cylindrical valve body, while being supported slidably by the needle supporting cylindrical inner wall. The nozzle needle is provided with a valve portion to be seated on the valve seat when the coil is de-energized and inside thereof with a cavity into which fuel is introduced. A fuel accumulation bore is provided between inner circumference of the cylindrical valve body extending axially from the valve seat to the needle supporting cylindrical inner wall and outer circumference of the nozzle needle.

With the construction mentioned above, the nozzle needle is further provided with an opening through which the cavity communicates with the fuel accumulation bore so that, when the valve portion leaves the valve seat upon energizing coil, the fuel accumulation bore communicates with the injection hole for fuel injection.

Since the nozzle needle is provided inside thereof with the cavity and with the opening through which the cavity communicates with the fuel accumulation bore, weight of the nozzle needle is lighter than that of the conventional fuel injection valve in which the nozzle needle has the cuts for forming the fuel and vapor passages between the armature accommodation bore and the fuel accumulation bore.

Preferably, the opening of the nozzle needle is opened to the highest position in the fuel accumulation bore to evacuate vapor smoothly.

It is preferable that the housing has a hollow into which fuel is flown from outside and the stator is provided with a penetrating bore communicating with the hollow of the housing at an axial end thereof and communicating with an armature accommodation bore at another axial end thereof, and the armature has a through-hole for making the armature accommodation bore on a side of the stator communicate with the cavity so that fuel is introduced from the hollow of the housing into the cavity. With this construction, the fuel injection valve becomes further lighter and more compact.

It is preferable that the nozzle needle penetrates axially along the through-hole of the armature until an axial end thereof protrudes out of an axial end of the armature toward the stator so that fuel is introduced into the cavity from the hollow of the housing via the penetrating bore. This will make it possible to manufacture the fuel injection valve at lower cost, since an air gap is automatically formed between the stator and the armature by the axial end of the nozzle needle protruding out of the end of the armature and coming in contact with the stator and, further, it is not necessary to cover the axial end of the nozzle needle with chromium thin film for reinforcement because the nozzle needle is inherently made of material having relatively higher stiffness.

Preferably, the opening of the nozzle needle is formed to axially stride over the needle supporting cylindrical inner wall so that the cavity communicates not only with the fuel accumulation bore but also with the armature accommodation bore on a side of the cylindrical valve body. With this

construction, vapor generated by heat is easily evacuated from the fuel accumulation bore to the armature accommodation bore through the opening. Accordingly, fluctuation of injection characteristic due to vapor is limited.

Further, it is preferable that the needle cylindrical inner wall, whose diameter is larger than a diameter of the valve seat, is formed to protrude radially inward out of the inner wall of the cylindrical valve body. Since a diameter of the valve seat are smaller than that of the needle supporting cylindrical inner wall, the seat valve, on which the valve portion of the nozzle needle is seated, is easily and accurately machined by inserting a cutting tool from a side of the needle supporting cylindrical inner wall into an inside of the cylindrical valve body.

Moreover, preferably, the nozzle needle is provided with a small diameter column portion whose axial end on a side of the injection hole constitutes the valve portion and with a large diameter column portion whose diameter is larger than that of the small diameter column portion and which is slidably supported by the needle supporting cylindrical inner wall.

BRIEF DESCRIPTION OF THE DRAWING

Other features and advantages of the present invention will be appreciated, as well as methods of operation and the function of the related parts, from a study of the following detailed description, the appended claims, and the drawings, all of which form a part of this application. In the drawings:

FIG. 1 is across sectional part view of a fuel injection valve according to a first embodiment of the present invention;

FIG. 2 is a cross sectional whole view of the fuel injection valve according to the first embodiment;

FIG. 3 is a cross sectional part view of a fuel injection valve according to a second embodiment of the present invention;

FIG. 4 is a cross sectional part view of a modified fuel injection valve according to the second embodiment;

FIG. 5 is a cross sectional part view of a fuel injection valve according to a third embodiment of the present invention; and

FIG. 6 is a cross sectional whole view of a conventional fuel injection valve as a prior art.

DETAILED DESCRIPTION OF THE PREFERRED EMBODIMENTS

(First Embodiment)

A fuel injection valve according to a first embodiment is described with reference to FIGS. 1 and 2.

As shown in FIG. 2, a valve body 29, a nozzle needle 26, an armature 25, a stator 22, an adjusting pipe 21, a spring 24 and a filter 11 are accommodated in a cylindrical member 14.

The cylindrical member 14, for example, made of composite magnetic material, is formed in pipe shape to have both of magnetic and non-magnetic portions. The cylindrical member 14 has the non-magnetic portion partly changed by heating and is provided with a magnetic pipe portion 14c, a non-magnetic pipe portion 14b and a magnetic pipe portion 14a, which are positioned upward in order from a lower end thereof on a side of fuel injection. The armature 25 is housed in an armature accommodation bore 14e of the cylindrical member 14 in a vicinity of a boundary between the non-magnetic pipe portion 14b and the magnetic pipe portion 14c. The valve body 29 and an injection hole plate 28 are

housed in the magnetic pipe portion 14c on a side of fuel injection. The filter 11, which filters foreign material in fuel, is installed in the cylindrical member 14 at an upper end on a fuel upstream side.

As shown in FIG. 1, the valve body 29, which is formed in pipe shape, is press fitted into and fixed by laser welding to an inner wall of the magnetic pipe portion 14c. An inner circumferential wall of the valve body 29 has a conical surface wall 29a, a large diameter cylindrical surface wall 29b, a conical surface wall 29c, a small diameter cylindrical surface wall 29d and a conical surface wall 29e, which are positioned in order from a side of fuel injection toward a side of fuel upstream. The conical surface wall 29a, whose diameter is smaller toward a side of fuel injection, is provided to form a valve seat on which a contact portion

15 26c of the nozzle needle 26 can be seated. The large diameter cylindrical surface wall 29b is provided to form a fuel accumulation bore 29f. A diameter of the conical surface wall 29 is smaller toward a side of fuel upstream. The small diameter cylindrical surface wall 29d constitutes a nozzle 20 needle supporting hole whose diameter is smaller than that of the fuel accumulation bore 29f. A diameter of the conical surface wall 29e is larger toward a side of fuel upstream.

The injection hole plate 28 in cup shape is press fitted into and fixed by laser welding to an inner wall of the magnetic 25 pipe portion 14c. The injection hole plate 28 is in contact with an end of the valve body 29 on a side of fuel injection. The injection hole plate 28 is formed in thin plate shape and provided in a center thereof with a plurality of injection holes 28a.

The nozzle needle 26 is made of stainless steel and formed in cylindrical shape having a bottom. The nozzle needle 26 is provided on a side of fuel upstream with a large diameter column portion 26e whose diameter is slightly smaller than an inner diameter of the small diameter cylindrical surface

35 wall 29d and provided on a side of fuel injection with a small diameter column portion 26d whose diameter is smaller than that of the large diameter column portion 26e on a side of fuel upstream. It is preferable that a diameter difference between the large and small diameter column portions 26e and 26d is more than 0.1 mm in view of obtaining lighter weight of the nozzle needle 26 and easily manufacturing the valve seat.

An end corner of the small diameter column portion 26d on a side of fuel injection is chamfered or tapered to form a 45 conical surface that constitutes the contact portion 26c. A diameter of the contact portion 26c, that is, a seat diameter, is smaller than that of the small diameter cylindrical surface wall 29d. To bring an outer wall of the large diameter column portion 26e in slidable contact with the small diameter cylindrical surface wall 29d, a slight clearance is formed therebetween. Most part of the large diameter column portion 26e is formed in thin cylinder shape and an inner circumferential wall 26a thereof constitutes an interior passage 26f. The interior passage 26f is formed by drilling a 50 hole from an end of the large diameter column portion 26e on a side of fuel upstream. Length of the drilled hole is deep to an extent that a bottom of the nozzle needle 26 sufficiently endures a shock caused on seating itself on the valve seat.

An axial length of the large diameter column portion 26e 60 is long to an extent that, when centerless machining forms the small diameter column portion 26d and the contact portion 26c, an outer circumferential wall of the large diameter column portion 26e can be held tightly by a chuck so that a center axis of the valve body does not deviate throughout a whole axial length thereof.

The large diameter column portion 26e is provided with outlet holes 26b that constitute openings of the interior

passage 26f. The outlet holes 26b are positioned circumferentially at 180-degree angular intervals so as to perforate the large diameter column portion 26e radially. One outlet hole 26b, instead of the two outlet holes 24, is sufficient enough to perform an operation of the present invention. Each of the outlet holes 26b is formed in shape of oval or flat oval whose major axis extends axially and whose major axis length is longer than axial length of the small diameter cylindrical surface wall 29d. A periphery of the outlet hole 26b on a side of fuel injection is located at a position lower than an axial end of the small diameter cylindrical surface wall 29d on a side of fuel injection and opened to the fuel accumulation bore 29f. Another periphery of the outlet hole 26b on a side of fuel upstream is located at a position higher than an axial end of the small diameter cylindrical surface wall 29d on a side of fuel upstream and opened to the armature accommodation bore 14e. The shape of the outlet hole 26b is not limited to oval or flat oval but may be circular.

The armature 25 is fixed by laser welding to an outer wall of the large diameter column portion 26 on a side of fuel upstream. The armature 25 is made of ferromagnetic material such as magnetic stainless steel and is formed in pipe shape having steps. Inner circumferential wall 25b of the armature 25 is provided in middle thereof with a ring shaped projection so as to form steps on axially opposite sides thereof. Inner diameter of the armature 25 at the ring shaped projection is smallest. The step of the armature 25 on a side of fuel upstream serves as a spring seat 25c. An interior passage 25e of the armature 25 and the interior passage 26f of the nozzle needle 26 communicate with each other. The armature is further provided at an end on a side of fuel upstream with a flange 25a. An outer circumferential wall of the flange 25a and an inner circumferential wall of the cylindrical member 14 are in slidable contact with each other so that a slight clearance is formed therebetween.

As the outer circumferential wall of the large diameter column portion 26e and the small diameter cylindrical wall 29d are in slidable contact with each other and the outer circumferential wall of the flange 25a and the inner circumferential wall of the cylindrical member 14 are in slidable contact with each other, the nozzle needle 26 moves reciprocatingly along a predetermined orbit. The armature 25 is provided at an axial end thereof on a side of fuel upstream with a ring shaped projection 25d which comes in contact with the stator 22 with an air gap between the axial end of the armature 25 other than the ring shaped projection 25d and an axial end of the stator 22. A surface of the ring shaped projection 25d that comes in contact with the stator 22 is coated with chromium thin film.

As shown in FIG. 2, the stator 22 is made of ferromagnetic material such as magnetic stainless steel and is formed in cylindrical shape. A surface of the stator 22 that comes in contact with the armature 25 is coated with chromium thin film. The adjusting pipe 21 is press fitted and fixed into an inner wall of the stator 22. Adjusting a press fitting amount of the adjusting pipe 21 allows to change preset biasing force of the spring 24, whose one end contacts the spring seat 25c of the armature 25 and whose another end contacts an end of the adjusting pipe 21. The adjusting pipe 21 may be fastened to stator 22 by screws instead of being press fitted thereto.

As shown in FIG. 2, a resin spool 30 is attached to outer circumference of the cylindrical member 14. A coil 31 is wound on outer circumference of the spool 30. An outer circumference of the cylindrical member 14 is covered with a resin mold 13 and provided with a connector portion 16 protruding out of the outer wall of the resin mold 13. A

terminal 12, which is connected in circuit with the coil 31, is embedded in the connector portion 16. The terminal is partly covered with a resin rib 17.

A magnetic member 23 covers around outer circumference of the coil 31. A fan shaped magnetic member 18 is disposed on a fuel upstream side of the coil 31 circumferentially at an angle of about 250 degrees not to interfere with the rib 17. A resin mold 15 is formed around outer circumferences of the magnetic members 18 and 23 and connected with the resin mold 13. The nozzle needle 26, the stator 22, the magnetic pipe portions 14a and 14c and the magnetic members 18 and 23 constitute a magnetic circuit through which magnetic flux passes on energizing the coil 31.

Fuel, which is flown into the cylindrical member 14 through the filter 11, is introduced to the fuel accumulation bore 29f from the outlet hole 26b via an interior of the adjusting pipe 21, an interior of the stator 22, the interior passage 25e of the armature 25 and the inner passage 26f of the nozzle needle 26 so that fuel reaches a portion where the contact portion 26c of the nozzle needle 26 is seated on the valve seat. When the contact portion 26c is seated on the valve seat, communication between the fuel accumulation bore 29f and the injection holes 28a is interrupted and, when the contact portion 26c leaves the valve seat, the fuel accumulation bore 29f communicates with the injection holes 28a.

Next, an operation of the fuel injection valve 1 is described.

Upon energizing the coil 31, the nozzle needle 26 is attracted toward the stator 22 against the biasing force of the spring 24. Accordingly, the contact portion 26c leaves the valve seat so that fuel is injected from the injection holes 28a.

Upon de-energizing the coil 31, the nozzle needle 26 receives the biasing force of the spring 24 acting in the valve closing direction so that the contact portion 26c is seated on the valve seat to finish the fuel injection from the injection holes 28a.

According to the fuel injection valve 1 mentioned above, 40 As the outer circumferential wall of the large diameter column portion 26e and the small diameter cylindrical wall 29d are in slidable contact with each other and the outer circumferential wall of the flange 25a and the inner circumferential wall of the cylindrical member 14 are in slidable contact with each other, the nozzle needle 26 moves reciprocatingly along the predetermined orbit without offsetting the center axis thereof. Accordingly, the contact portion 26c of the small diameter column portion 26d comes in contact accurately with a predetermined seat position on the conical surface wall 29a.

During engine operation, vapor tends to be generated in fuel by heat in the fuel accumulation bore 29f. According to the fuel injection valve 1, the vapor moves toward the fuel upstream side from the fuel accumulation bore 29f through 55 the outlet hole 26b so that generation of the vapor does not affect adversely on fuel injection characteristic. Further, the outlet hole 26b makes it possible to reduce frictional resistance between the nozzle needle 26 and the valve body 29 so that the quick response characteristic of the nozzle needle 26 is secured since a surface area where the nozzle needle 26 and the valve body 29 are in slidable contact with each other is relatively small.

Furthermore, as the interior passage 26f of the nozzle needle 26 constitutes a fuel passage, the outer diameter of the large diameter column portion 26e is relatively small and is slightly larger than or nearly equal to that of the contact portion 26c. A large part of the nozzle needle 26 is consti-

tuted by the large diameter column portion **26e** whose wall thickness is relatively thin. Accordingly, mass of the movable member integrally composed of the nozzle needle **26** and the armature **25** becomes smaller, resulting in improving the quick response characteristic of the nozzle needle **26**.

Moreover, as the small diameter column portion **26d** is formed on the nozzle needle **26** on a side of fuel injection, the valve seat can be easily and accurately manufactured. In more details, it is generally required to highly accurately machine the seat portion on the conical surface wall **29a** on which the contact portion **26c** is fluid-tightly seated. Since the seat diameter is smaller than an inner diameter of the small diameter cylindrical surface wall **29d** of the valve body which slidably supports the nozzle needle **26**, the seat portion on the conical surface wall **29a** can be accurately machined by inserting a cutting tool into the fuel accumulation bore **29f** from a side of fuel upstream after the small diameter cylindrical surface wall **29d**, the conical surface wall **29c**, the large diameter cylindrical surface wall **29b** and conical surface wall **29a** are machined.

As the fuel injection valve **1** has a construction that the valve body **29** supports the large diameter column portion **26e** of the nozzle needle **26** on a side of fuel upstream, the nozzle needle **26** can be easily and accurately machined. That is, it is necessary to machine coaxially and accurately the large diameter column portion **26e** and the contact portion **26c** for securing valve fluid-tightness. Since the large diameter column portion **26e**, whose axial length is relatively long, is firmly fixed by the chuck, centerless machining can accurately form the contact portion **26c**.

(Second Embodiment)

A fuel injection valve according to a second embodiment is described with reference to FIG. 3. A construction of the fuel injection valve not shown in FIG. 3 is substantially same as the fuel injection valve **1** of the first embodiment. The construction of the second embodiment substantially similar as that of the first embodiment is described with the same reference number as the first embodiment.

A valve body **41** is formed in shape of a cylinder whose peripheries of both opening ends protrude radially and inwardly. An inner circumferential wall of the valve body **41** has a conical surface wall **41a**, a large diameter cylindrical surface wall **41b**, a step surface wall **41c** and a small diameter cylindrical surface wall **41d**, which are positioned in order from a side of fuel injection toward a side of fuel upstream. The conical surface wall **41a**, whose diameter is smaller toward a side of fuel injection, is provided to form a valve seat on which a contact portion **42b** of the nozzle needle **42** can be seated. The large diameter cylindrical surface wall **41b** is provided to form a fuel accumulation bore **41e**. The small diameter cylindrical surface wall **41d** constitutes a nozzle needle supporting hole whose diameter is smaller than that of the fuel accumulation bore **41e**.

The nozzle needle **42** is made of stainless steel and formed in cylindrical shape having a bottom. The nozzle needle **42** has a column wall **42d** whose diameter is identical from a side of fuel injection to a side of fuel upstream. To bring the column wall **42d** in slidable contact with the small diameter cylindrical surface wall **41d**, a slight clearance is formed therebetween. An interior passage **42c** is formed by drilling a hole from an end of the nozzle needle **42** on a side of fuel upstream. Length of the drilled hole is deep to an extent that a bottom of the nozzle needle **42** sufficiently endures a shock caused on seating itself on the valve seat. An outlet hole **42**, which constitute an opening of the interior passage **42c**, is formed in oval or flat oval shape.

An interior space **40d**, which is formed by an inner circumferential wall **40b** of an armature **40**, and the interior

passage **42c** of the nozzle needle **42** communicate with each other. Outer circumference of a flange **40c** on the outer circumference of the armature **40** is in slidable contact with the inner circumferential wall **14d** of the cylindrical member **14A**. The armature **40** is provided at a step portion thereof with vapor passages **40a**, through which an armature accommodation bore **14e** and the interior space **40d** of the armature **40** communicate with each other. The vapor passages **40a** serve to move vapor included in fuel toward a side of fuel upstream in the armature accommodation bore **14e**.

According to the second embodiment, it is easy to form accurately the contact portion **42b** by centerless machining since the nozzle needle **42** has the column wall **42d** whose diameter is identical axially. Further, as the fuel passage **15** extending from the interior space **40d** of the armature **40** to the fuel accumulation bore **41e** is formed through the interior passage **42c** and the outlet hole **42a** of the nozzle needle **42**, the mass of the nozzle needle **42** is smaller so that the quicker response of the nozzle needle **42** may be secured.

As an alternative, the nozzle needle **43** may be formed to penetrate axially the armature **40**, as shown in FIG. 4. An axial end **43a** of the nozzle needle **42** protrudes out of the end of the armature **40** on a side of the stator so as to come in contact with stator **22**. With this construction, as it is not necessary to cover the axial end **43a** with the chromium thin film for reinforcement, the fuel injection valve is manufactured at lower cost.

(Third Embodiment)

A fuel injection valve according to a third embodiment is described with reference to FIG. 5. A construction of the fuel injection valve not shown in FIG. 5 is substantially same as the fuel injection valve **1** of the first embodiment. The construction of the third embodiment substantially similar as that of the first embodiment is described with the same reference number as the first embodiment.

A valve body **52** is formed in shape of a cylinder whose opening end on a side of fuel injection protrudes radially and inwardly. The valve body **52** is provided on an inner circumferential wall thereof with a conical surface wall **52b** on a side of fuel injection and a cylindrical surface wall **52a** on a side of fuel upstream. The conical surface wall **52b**, whose inner wall diameter is smaller toward a side of fuel injection, constitutes a valve seat on which a contact portion **51c** of a nozzle needle **51** is seated. The cylindrical surface wall **52a** constitutes a fuel accumulation bore **52c**.

The nozzle needle **51**, which is made of stainless steel, is formed in cylindrical shape having a bottom. The nozzle needle **51** is provided on a side of fuel upstream with a large diameter column portion **51e** whose diameter is slightly smaller than an inner diameter of the cylindrical surface wall **52a** and provided on a side of fuel injection with a small diameter column portion **51d** whose diameter is smaller than that of the large diameter column portion **51e**. An end corner of the small diameter column portion **51d** on a side of fuel injection is chamfered or tapered to form a conical surface that constitutes the contact portion **51c**. A diameter of the contact portion **51c**, that is, a seat diameter, is smaller than that of the cylindrical surface wall **52a**.

An axial end **51g** of the large diameter column portion **51e** on a side of fuel upstream penetrates an armature **50** so as to protrude out of the end of the armature on a side of the stator. The axial end **51g** comes in contact with the stator **22** with an air gap between the axial end of the armature and an axial end of the stator **22**. An outer circumferential wall of the large diameter column portion **51e** and the cylindrical surface wall **52a** are in slidable contact with each other so that a slight clearance is formed therebetween. An interior

passage **51a** is formed by drilling a hole from an end of the large diameter column portion **51e** on a side of fuel upstream. Length of the drilled hole is deep to an extent that a bottom of the nozzle needle **51** sufficiently endures a shock caused on seating itself on the valve seat.

5
Outlet holes **51b**, which extends from the large diameter column portion **51e** to the small diameter column portion **51d**, are positioned circumferentially at 180-degree angular intervals so as to perforate the large diameter column portion **51e** radially. The outlet hole **51b** is formed in oval or flat oval shape. A periphery of the outlet hole **51b** on a side of fuel injection is formed on an outer circumferential wall of the small diameter column portion **51d** and another periphery thereof on a side of fuel upstream is formed on an outer circumferential wall of the large diameter column portion **51e** at a position on a side of fuel upstream with respect to an axial end **52d** of a valve body **52**.

According to the third embodiment, the interior passage **51a** of the nozzle needle **51** communicates with injection holes **28a** via a fuel accumulation bore **52** which is formed between the valve body **52** and the small diameter column portion **51d**. Wall thickness of most part of the nozzle needle **51** is thinner. Accordingly, mass of a movable member composed of the nozzle needle **51** and the armature **50** is relatively small so that the nozzle needle **51** has quicker response characteristic.

15
What is claimed is:

1. A fuel injection valve comprising:

a housing;

a stator fixed to the housing;

a cylindrical valve body fixed to the housing, the cylindrical valve body being provided at an axial end thereof on a side opposite to the stator with at least an injection hole and having a valve seat protruding radially inward out of an inner wall thereof, which is positioned on a side of the stator with respect to the injection hole, and a needle supporting cylindrical inner wall, which is positioned on a side of the stator with respect to the valve seat;

30
an armature accommodation bore provided in the housing between the stator and the cylindrical valve body;

an armature movable in the armature accommodation bore;

40
a coil for exerting an electromagnetic attracting force on the armature so as to be attracted toward the stator when energized;

45
a nozzle needle fixed to the armature and movable together with the armature in the cylindrical valve body and the armature accommodation bore, while being supported slidably by the needle supporting cylindrical inner wall, the nozzle needle being provided with a valve portion to be seated on the valve seat when the coil is de-energized and inside thereof with a cavity into which fuel is introduced; and

50
a fuel accumulation bore provided between an inner circumference of the cylindrical valve body extending axially from the valve seat to the needle supporting cylindrical inner wall and an outer circumference of the nozzle needle;

55
wherein the nozzle needle is provided with an opening through which the cavity communicates with the fuel accumulation bore so that, when the valve portion leaves the valve seat upon energizing the coil, the fuel accumulation bore communicates with the injection hole for fuel injection; and

60
the housing has a hollow into which fuel is flown from outside and the stator is provided with a penetrating

bore communicating with the hollow of the housing at an axial end thereof and communicating with the armature accommodation bore at another axial end thereof, and the armature has a through-hole for making the armature accommodation bore on a side of the stator communicate with the cavity so that fuel is introduced from the hollow of the housing into the cavity.

2. A fuel injection valve according to claim 1, wherein the nozzle needle penetrates axially along the through-hole of the armature until an axial end thereof protrudes out of an axial end of the armature toward the stator so that fuel is introduced into the cavity from the hollow of the housing via the penetrating bore.

10
3. A fuel injection valve according to claim 1, wherein the through hole of the armature communicates with the armature accommodation bore on the side of the stator at an axial end thereof and communicates with the cavity at another axial end thereof so that fuel is introduced into the cavity from the hollow of the housing via the penetrating bore and the through-hole.

20
4. A fuel injection valve according to claim 3, wherein the armature is provided at an axial end thereof on a side of the nozzle needle with an aperture through which the armature accommodation bore communicates with the through-hole.

25
5. A fuel injection valve comprising:

a housing;

a stator fixed to the housing;

a cylindrical valve body fixed to the housing, the cylindrical valve body being provided at an axial end thereof on a side opposite to the stator with at least an injection hole and having a valve seat protruding radially inward out of an inner wall thereof, which is positioned on a side of the stator with respect to the injection hole, and a needle supporting cylindrical inner wall, which is positioned on a side of the stator with respect to the valve seat;

30
an armature accommodation bore provided in the housing between the stator and the cylindrical valve body;

an armature movable in the armature accommodation bore;

35
a coil for exerting an electromagnetic attracting force on the armature so as to be attracted toward the stator when energized;

40
a nozzle needle fixed to the armature and movable together with the armature in the cylindrical valve body and the armature accommodation bore, while being supported slidably by the needle supporting cylindrical inner wall, the nozzle needle being provided with a valve portion to be seated on the valve seat when the coil is de-energized and inside thereof with a cavity into which fuel is introduced; and

45
a fuel accumulation bore provided between an inner circumference of the cylindrical valve body extending axially from the valve seat to the needle supporting cylindrical inner wall and an outer circumference of the nozzle needle;

50
wherein the nozzle needle is provided with an opening through which the cavity communicates with the fuel accumulation bore so that, when the valve portion leaves the valve seat upon energizing the coil, the fuel accumulation bore communicates with the injection hole for fuel injection; and

55
the opening is formed to axially stride over the needle supporting cylindrical inner wall so that the cavity

communicates not only with the fuel accumulation bore but also with the armature accommodation bore on a side of the cylindrical valve body.

6. A fuel injection valve comprising:

a housing;

a stator fixed to the housing;

a cylindrical valve body fixed to the housing, the cylindrical valve body being provided at an axial end thereof on a side opposite to the stator with at least an injection hole and having a valve seat protruding radially inward out of an inner wall thereof, which is positioned on a side of the stator with respect to the injection hole, and a needle supporting cylindrical inner wall, which is positioned on a side of the stator with respect to the valve seat;

an armature accommodation bore provided in the housing between the stator and the cylindrical valve body;

an armature movable in the armature accommodation bore;

a coil for exerting an electromagnetic attracting force on the armature so as to be attracted toward the stator when energized;

a nozzle needle fixed to the armature and movable together with the armature in the cylindrical valve body and the armature accommodation bore, while being supported slidably by the needle supporting cylindrical inner wall, the nozzle needle being provided with a valve portion to be seated on the valve seat when the coil is de-energized and inside thereof with a cavity into which fuel is introduced; and

a fuel accumulation bore provided between an inner circumference of the cylindrical valve body extending axially from the valve seat to the needle supporting cylindrical inner wall and an outer circumference of the nozzle needle;

wherein the nozzle needle is provided with an opening through which the cavity communicates with the fuel accumulation bore so that, when the valve portion leaves the valve seat upon energizing the coil, the fuel accumulation bore communicates with the injection hole for fuel injection; and

the nozzle needle is provided with a small diameter column portion whose axial end on a side of the injection hole constitutes the valve portion and with a large diameter column portion whose diameter is larger than that of the small diameter column portion and which is slidably supported by the needle supporting cylindrical inner wall.

7. A fuel injection valve comprising:

a housing;

a stator fixed to the housing;

a cylindrical valve body fixed to the housing, the cylindrical valve body being provided at an axial end thereof on a side opposite to the stator with at least an injection hole and having a valve seat protruding radially inward out of an inner wall thereof, which is positioned on a side of the stator with respect to the injection hole, and a needle supporting cylindrical inner wall, which is positioned on a side of the stator with respect to the valve seat;

an armature accommodation bore provided in the housing between the stator and the cylindrical valve body;

an armature movable in the armature accommodation bore;

a coil for exerting an electromagnetic attracting force on the armature so as to be attracted toward the stator when energized;

a nozzle needle fixed to the armature and movable together with the armature in the cylindrical valve body and the armature accommodation bore, while being supported slidably by the needle supporting cylindrical inner wall, the nozzle needle being provided with a valve portion to be seated on the valve seat when the coil is de-energized and inside thereof with a cavity into which fuel is introduced; and

a fuel accumulation bore provided between an inner circumference of the cylindrical valve body extending axially from the valve seat to the needle supporting cylindrical inner wall and an outer circumference of the nozzle needle;

wherein the nozzle needle is provided with an opening through which the cavity communicates with the fuel accumulation bore so that, when the valve portion leaves the valve seat upon energizing the coil, the fuel accumulation bore communicates with the injection hole for fuel injection; and

the needle supporting cylindrical inner wall, whose diameter is larger than a diameter of the valve seat, is formed to protrude radially inward out of the inner wall of the cylindrical valve body.

8. A fuel injection valve comprising:

a housing;

a stator fixed to the housing;

a cylindrical valve body fixed to the housing, the cylindrical valve body being provided at an axial end thereof on a side opposite to the stator with at least an injection hole and having a valve seat protruding radially inward out of an inner wall thereof, which is positioned on a side of the stator with respect to the injection hole, and a needle supporting cylindrical inner wall, which is positioned on a side of the stator with respect to the valve seat;

an armature accommodation bore provided in the housing between the stator and the cylindrical valve body;

an armature movable in the armature accommodation bore;

a coil for exerting an electromagnetic attracting force on the armature so as to be attracted toward the stator when energized;

a nozzle needle fixed to the armature and movable together with the armature in the cylindrical valve body and the armature accommodation bore, while being supported slidably by the needle supporting cylindrical inner wall, the nozzle needle being provided with a valve portion to be seated on the valve seat when the coil is de-energized and inside thereof with a cavity into which fuel is introduced; and

a fuel accumulation bore provided between an inner circumference of the cylindrical valve body extending axially from the valve seat to the needle supporting cylindrical inner wall and an outer circumference of the nozzle needle;

wherein the nozzle needle is provided with an opening through which the cavity communicates with the fuel accumulation bore so that, when the valve portion leaves the valve seat upon energizing the coil, the fuel accumulation bore communicates with the injection hole for fuel injection; and

an outer circumference of the armature is in slidable contact with a circumferential wall constituting the

13

armature accommodation bore in the housing so that the armature is slidably supported by axially spaced two supporting points.

9. A fuel injection valve comprising:

a housing;

a stator fixed to the housing;

a cylindrical valve body fixed to the housing, the cylindrical valve body being provided at an axial end thereof on a side opposite to the stator with at least an injection hole and having a valve seat protruding radially inward out of an inner wall thereof, which is positioned on a side of the stator with respect to the injection hole, and a needle supporting cylindrical inner wall, which is positioned on a side of the stator with respect to the valve seat;

an armature accommodation bore provided in the housing between the stator and the cylindrical valve body;

an armature movable in the armature accommodation bore;

a coil for exerting an electromagnetic attracting force on the armature so as to be attracted toward the stator when energized;

a nozzle needle fixed to the armature and movable together with the armature in the cylindrical valve body and the armature accommodation bore, while being supported slidably by the needle supporting cylindrical inner wall, the nozzle needle being provided with a valve portion to be seated on the valve seat when the

5

14

coil is de-energized and inside thereof with a cavity into which fuel is introduced; and

a fuel accumulation bore provided between an inner circumference of the cylindrical valve body extending axially from the valve seat to the needle supporting cylindrical inner wall and an outer circumference of the nozzle needle,

wherein the nozzle needle is provided on an outer circumference thereof with an opening at least part of which is opened to the fuel accommodation bore from the cavity so that the fuel introduced into the cavity flows through the opening to the fuel accumulation bore, and when the valve portion leaves the valve seat upon energizing the coil, the fuel accumulation bore communicates with the injection hole for fuel injection.

10. A fuel injection valve according to claim 9, wherein another part of the opening is radially opposed to the needle supporting cylindrical wall.

11. A fuel injection valve according to claim 9, wherein the valve seat and the needle supporting cylindrical inner wall are integrally formed into a single piece.

12. A fuel injection valve according to claim 9, wherein another part of the opening is opened to the armature accommodation bore from the cavity so that the opening axially straddles over the needle supporting cylindrical inner wall.
